UNITED STATES PATENT OFFICE.

EARL M. TRAMMELL AND WILLIAM C. CAROTHERS, OF WACO, TEXAS.

IRONING-BOARD.

1,384,361.

Specification of Letters Patent. Patented July 12, 1921.

Application filed December 27, 1920. Serial No. 433,285.

To all whom it may concern:

Be it known that we, EARL M. TRAMMELL and WILLIAM C. CAROTHERS, both citizens of the United States, residing at Waco, 5 in the county of McLennan and State of Texas, have invented certain new and useful Improvements in Ironing-Boards, of which the following is a specification.

This invention relates to ironing boards 10 of the class in which the board is placed, when not in use, in a cabinet or closet attached to or built into the wall of the room and in which it is concealed and so held as to present no obstruction in the room, the 15 board being so mounted in a cabinet that when desired it may be lowered from a vertical to a horizontal position in condition for use. In many such ironing boards their inner or lower ends are pivotally connected 20 with the sides of the cabinet, while their outer ends carry braces or legs for their support, and while such boards are very useful and serviceable they nevertheless are not conveniently used when ironing seamed 25 garments such as dresses and skirts where it is necessary or desirable to insert the board into the garment.

According to our invention, we provide a cabinet which may be either built into or 30 attached to the side wall of a room, and we provide an ironing board which has no braces or legs at its outer end but is so connected at its inner end with the cabinet that it may be securely held when either raised 35 or lowered. This is accomplished by forming slots or grooves of suitable shape in the sides of the cabinet and providing the sides of the inner end of the board with studs which engage these grooves or slots and are 40 free to move therein. A recess is formed in the back portion of the cabinet with which the rear end of the board engages when lowered. The arrangement is such that when the board is raised to a vertical 45 position within the cabinet its rear or lower end rests on the bottom of the cabinet, but when the board is lowered to a horizontal position its rear end enters the recess and the rear portion of the board rests on the 50 bottom of the cabinet. In this way the board is so firmly and securely held that braces or legs for its outer portion are rendered unnecessary.

In the accompanying drawings:—

55 Figure 1 is a perspective view of a com-

bined ironing board and cabinet embodying our improvements.

Figs. 2 and 3 are on an enlarged scale.

Fig. 2 is a vertical section through the lower portion of the cabinet and indicates 60 the connection between the inner or rear end of the board and the cabinet.

Fig. 3 is a local horizontal section further illustrating the invention.

The cabinet may be built into the side 65 wall of a room or it may be attached thereto in any suitable way. In general it may be of any suitable construction. As shown, it comprises a casing A having a door B, the door opening being sufficiently long to 70 admit the ironing board C when the latter is raised to a vertical position. The door B is hinged to the casing, as indicated at c. A closet D below the cabinet may be used 75 to store irons and other accessories.

In each side wall E of the cabinet we form 80 a slot or groove e which extends vertically downward, as indicated at e', and is then bent rearwardly, as indicated at e'', the walls of the part e'' of the groove or slot being curved, as shown. These slots terminate a short distance above the bottom of the cabinet. The two slots on opposite sides of the cabinet are of the same shape and each of 85 these slots or grooves is engaged by a stud f extending laterally from the ironing board near its rear end. In the back wall of the cabinet we form a recess g which is preferably formed in an inserted block or board of relatively thick material. The recess is 90 adapted to receive the rear end of the board C when the latter is lowered, the slots e', e'' being so shaped as to guide the rear end of the board into the recess when the board is lowered.

95 When the board is raised to a vertical position its rear or lower end rests on the bottom of the cabinet and its upper end may be tilted back against the rear wall thereof. At this time the door of the cabinet may be 100 closed.

When it is desired to use the board the door may be opened and then by taking hold of the upper portion of the board it may be tilted forward and downward, as indicated by dotted lines in Fig. 2. While being thus lowered the studs follow the grooves or slots and the rear end of the board is guided into the recess g.

When the board is lowered into the posi- 110

tion shown by full lines in Fig. 2, its rear end enters the groove as shown while its rear portion rests on the bottom *a* of the cabinet. Any tendency of the board to lower at its front or outer end when pressure is applied will be resisted by the upper wall *g'* of the recess *g* while the bottom *a* of the cabinet provides a firm support for the rear portion of the board. It will thus be seen that the outer supporting braces or legs, often employed in this class of boards, are by our invention rendered unnecessary. It will be further observed that the cabinet and the board are of the very simplest construction, can be made at low cost but at the same time are strong and durable and easily installed.

15 We claim as our invention:—

The combination with a cabinet having a horizontal bottom and vertical side walls

and having a recess in its back wall and a 20 groove in each side wall near its front and above its bottom, each of said grooves having an upper, straight, vertical portion and a rearwardly curved lower portion terminating above the bottom of the cabinet, and an 25 ironing-board having studs on its opposite sides entering the grooves in the side walls of the cabinet, and a rear portion adapted to enter the recess in the rear wall of the cabinet and to rest on the bottom of the 30 cabinet when the ironing-board is in a horizontal position and also to rest on the bottom of the cabinet when the ironing-board is in a vertical position.

In testimony whereof we have hereunto 35 subscribed our names.

EARL M. TRAMMELL.

WILLIAM C. CAROTHERS.
